UNITED STATES PATENT OFFICE.

BURNHAM C. STICKNEY, OF ELIZABETH, NEW JERSEY, ASSIGNOR TO JOHN T. UNDERWOOD, OF BROOKLYN, NEW YORK.

COMBINED TYPE-WRITING AND COMPUTING MACHINE.

1,071,273.

Specification of Letters Patent. Patented Aug. 26, 1913.

Application filed July 10, 1911. Serial No. 637,633.

To all whom it may concern:

Be it known that I, BURNHAM C. STICKNEY, a citizen of the United States, residing in Elizabeth, in the county of Union and 5 State of New Jersey, have invented certain new and useful Improvements in Combined Type-Writing and Computing Machines, of which the following is a specification.

This invention relates to combined type-writing and adding machines, and more especially to those of the class illustrated in the pending application of Walter Wright, Serial No. 574,813, filed August 1, 1910. In said application is illustrated an adding 10 mechanism comprising two primary elements, one being a master wheel and the other being a set of computing wheels, and one of said primary elements is connected to the letter-feeding carriage of the type-writing machine to travel therewith step-by-step, so that the master wheel shall be properly presented to the computing wheels in succession. In said application, such 15 connection between the typewriter carriage and the primary elements of the computing mechanism is effected intermittently; a hook being connected to said primary elements, and certain lugs being provided upon the typewriter carriage to be engaged and disengaged in succession by said hook, so that during the writing of a single line the various numbers which are written in different columns may be accumulated on the computing mechanism, thus effecting what 20 is known as cross adding. The lugs are shown in said application as adjustable to different points along said carriage.

One of the objects of my invention is to avoid the necessity of readjusting the lugs 40 from time to time as different classes of work are being produced, as in resetting the lugs the operator is liable to make errors, thus leading to confusion and loss of time.

According to my improvements, a special 45 bar is demountably secured upon the typewriter carriage, and has fixed thereon a set of lugs which have unchangeable positions, or in other words are not adjustable. When the operator has a certain class of work to 50 do, he needs only to attach said bar to the paper carriage, and then the cross computation may be proceeded with, without attending to any adjustment, thus saving time and labor and avoiding mistakes. The bar 55 is provided with a tooth or dowel to engage

one of the teeth on the rack bar which ordinarily carries the column stops, so that the bar is accurately positioned, and the lugs thereon are sure to perform their proper functions without liability of error. 60

The invention is useful whether one or several columns on a work sheet are to be computed, since the typewriting machine may be used for ordinary purposes without computing; and at any time the operator, if 65 he desires to perform a computation, may insert the novel bar in the machine, and thereafter the computing mechanism will operate at the proper point, so that it is unnecessary for the operator to adjust a lug 70 or either to remember or to ascertain where said lug is to be placed. In this way the operator can fill in similar blanks from time to time, and perform computation in the proper column or columns thereon, while at 75 any time he may use the machine for typewriting without computing, by simply removing the novel bar from the machine.

The invention is also useful in connection 80 with other styles of computing mechanism than that shown in said application, as for instance where it is desired only to add vertically and not to cross add.

The drawing is a perspective front view 85 of the invention applied to the Underwood combined typewriting and computing machine, as set forth in said application.

As set forth in said application, a platen is mounted on a typewriter carriage 6, and the latter has a rack 21 to carry any of a 90 series of tabulating stops 18, which cooperate with key-set denomination stops 17 in the usual manner. A hook 55 is connected to the master wheel, whereby said master wheel is intermittently connected to the carriage 6 to travel therewith. The hook is automatically disconnected from the carriage by a trip 70 which engages a cam 69 on the hook to pull the same down and out of connection with the carriage; a spring 100 tending to lift said hook.

In place of the adjustable lugs shown in said application for engagement by said hook, I show a series of fixed lugs 80 which are formed by cutting and bending down a 105 portion of a sheet metal bar 81 which extends along the rack 21 forwardly thereof, and high enough to escape the column stops 18, so that the latter may be adjusted wherever desired along the rack 21, usually in 110

alinement with the lugs 80. This bar is demountably secured upon the carriage by means of thumb screws 82 which pass down through ears 83 on the ends of the bar, and are threaded into the ends of racks 21. Arms 84 are fixed upon the typewriter carriage 6, and extending rearwardly therefrom, and carrying at their rear ends said column stop rack 21, said thumb screws 82 passing through slots in said ears 83, so that the bar may be adjusted a trifle endwise until a tooth or dowel 85 thereon is fitted into one of the notches in the column stop bar 21, whereby the lugs 80 are brought mechanically into the exact position required for coöperation with said hook 55. Thus, by merely inserting said bar in the machine, the same is set for the desired operation of the computing mechanism, without the necessity of remembering where to set a lot of lugs, and without the risk of setting them in the wrong place, or the necessity of making tests to see if they have been rightly placed. Said rack bar 21, during the construction of the typewriting machine, is adjusted endwise to a minute extent by means of a thumb nut 60* which is threaded upon a stud 86 which projects from the end of the rack 21; said thumb nut comprising a button which works in a notch 87 in one of the arms 84, so that by turning the nut, said rack 21 may be adjusted as required. A set nut 88 is then employed to secure the rack. It will be seen that this adjustment answers also for the lug bar 81, since the latter is connected by the tooth 85 always to the same notch in the bar 21. Said hook 55 is connected to and disconnected from the lugs 80 in succession in the manner which will be understood by reference to said application.

Variations may be resorted to within the scope of the invention, and portions of the improvements may be used without others.

Having thus described my invention, I claim:

1. In a combined typewriting and computing machine, the combination with a typewriter carriage, a rack on said carriage, mechanism coöperating with said rack to determine the position of said carriage, and

a bar having a plurality of projecting members thereon for determining the position of a traveling element of the computing part of the machine; said rack and bar being connected so that adjustment of said rack also adjusts said bar relatively to the carriage. 55

2. In a combined typewriting and computing machine, the combination with a typewriter carriage, a rack on said carriage, mechanism coöperating with said rack to determine the position of said carriage, a bar having a plurality of projecting members thereon for determining the position of a traveling element of the computing part of the machine, and a tooth on said bar engaging between the teeth of said rack to determine the relative position of said rack and said bar. 70

3. In a combined typewriting and computing machine, the combination with a typewriter carriage, a rack on said carriage, mechanism coöperating with said rack to determine the position of said carriage, a bar having a plurality of projecting members thereon for determining the position of a traveling element of the computing part of the machine, a tooth on said bar engaging between the teeth of said rack to determine the relative position of said rack and said bar, and means for detachably securing said bar on said rack. 75

4. In a combined typewriting and computing machine, the combination with a typewriter carriage, a rack on said carriage, mechanism coöperating with said rack to determine the position of said carriage, a bar having a plurality of projecting members thereon for determining the position of a traveling element of the computing part of the machine, a tooth on said bar engaging between the teeth of said rack to determine the relative position of said rack and said bar, and means for effecting fine adjustments of said bar and said rack for a distance less than a letter-space movement of the travel of the carriage. 90

BURNHAM C. STICKNEY.
